Wesley S. Barr
ATTORNEY

UNITED STATES PATENT OFFICE.

WILLARD H. KEMPTON, OF WILKINSBURG, PENNSYLVANIA, ASSIGNOR TO WESTINGHOUSE ELECTRIC & MANUFACTURING COMPANY, A CORPORATION OF PENNSYLVANIA.

SWITCHBOARD STRUCTURE.

Application filed July 13, 1922. Serial No. 574,761.

To all whom it may concern:

Be it known that I, WILLARD H. KEMPTON, a citizen of the United States, and a resident of Wilkinsburg, in the county of 5 Allegheny and State of Pennsylvania, have invented a new and useful Improvement in Switchboard Structures, of which the following is a specification.

My invention relates to switchboard structures and particularly to structures for securing an insulating instrument base to a switchboard or insulating panel.

One object of my invention is to provide a fastening means for attaching an insulating instrument base to an insulating switchboard or panel in such manner that the strain imposed by the fastening members is uniformly distributed, thus eliminating the danger of fracture of the insulating base.

Another object of my invention is to provide a structure, having the above characteristics, that is inexpensive to manufacture and which may be readily applied to standard switchboards and base structures.

In certain installations, it has been customary to secure the instrument base to a switchboard by means of threaded bolts, the base being drawn securely against the outer face of the switchboard or panel. In commercial structures of this character, surfaces of the rear face of the insulating base are usually uneven and the surfaces of the switchboard may be warped out of a true plane. In such cases the insulating base, 35 when drawn into engagement with the switchboard or panel, is subjected to uneven strains and frequently is fractured during the assembly operation. Fractures may also occur after the base has been assembled and 40 after the switchboard has been shipped in consequence of such uneven stresses.

These and other objects, that will be made apparent throughout the further description of my invention, are attained by means of 45 the switchboard structures hereinafter described, and illustrated in the accompanying drawings, wherein:

Figure 1 is a plan view of a base member assembled upon a switchboard or panel;

Fig. 2 is a view, partially in elevation and partially in vertical section, of the fastening mechanism and the base and panel structures;

Fig. 3 is a vertical section through a panel

and base, showing a modified form of fastening device, and

Fig. 4 is a similar view showing a further modification of the fastening device.

Referring to the drawings, a switchboard or insulating panel 5 is shown upon which 60 is mounted an instrument-supporting insulating base 6. Electrical devices or instruments of any type, such as switches, fuses, current-measuring instruments, etc., may be mounted upon the insulating base. The 65 support 5 and the base 6 are provided with perforations 7 and 8, respectively, into which four fastening members 9 are inserted. The heads 11 of the bolts are maintained in a fixed predetermined spaced relation to the support 5 by means of metal sleeves 12 that are slidably mounted upon the bolts 9 and are clamped between the heads 11 and the support 5 when the nuts 13 are tightened.

It will be seen that the base 6 is, therefore, slidably mounted for movement longitudinally of the bolts between the heads 11 and the support 5. Spring washers 14 are mounted on the bolts between the base and 80 the support to yieldingly press the base 6 into engagement with the heads 11 of the bolts. The base is, therefore, yieldingly supported in spaced relation to the switchboard or support 5. The resilient pressure 85 exerted by the spring washers is sufficient to firmly retain the base 6 in a fixed position against the heads of the bolts but, at no time, is it sufficient to cause fracture of the base, regardless of the irregularities of the 90 surfaces of the base. The sleeves 12 prevent compression of the spring washers beyond a predetermined limit and, therefore, the danger of fracture of the base is eliminated.

Fig. 3 shows a modified form of fastening member wherein the shank 15 of the bolt is of greater diameter than the threaded portion 16 thereof. A shoulder 17 is provided by this construction upon which a metal washer 18 is seated after a felt washer 19 100 has been placed upon the bolt. The shoulder 17 and washer 18 limit the inward movement of the head 11 of the bolt, and the felt washer, which is under compression when the base is assembled upon the support, 105 firmly presses the base 6 against the heads 11 of the bolts.

Fig. 4 illustrates a further modification

of the fastening device. A standard bolt is provided with upstruck lugs 21 which constitute a seat for a metal washer 22. The lugs and washer limit inward movement of the head 11 of the bolt 9 and, therefore, function similarly to the sleeve 12 illustrated in Figs. 1 and 2. A spring washer 14 serves to press the base against the heads of the bolt.

While I have illustrated and described but three embodiments of my invention, it will be apparent to those skilled in the art that various changes, modifications, substitutions, additions and omissions may be made therein without departing from the spirit and scope of my invention, as set forth in the appended claims.

I claim as my invention:

1. A fastening member for securing a base member to a support comprising a bolt having an enlarged portion for engaging the base and limiting outward movement thereof with respect to the support, means limiting inward movement of the enlarged portion, and a yielding means between the base and the support for yieldingly pressing the base into engagement with the enlarged portion of the bolt and retaining the base in spaced relation to the support.
2. A fastening member for securing a base member to a support comprising a bolt threaded at one end for receiving a threaded nut and having an enlarged portion for engaging the base and limiting outward movement thereof with respect to the support, a sleeve on the shank of the bolt for limiting inward movement of the enlarged portion thereof, a nut for the bolt and a yielding means between the base and the support for yieldingly pressing the base into engagement with the enlarged portion of the bolt and retaining the base in spaced relation to the support.
3. A fastening member for securing a per-

forate base member to a support having a perforation aligned with a perforation in the base comprising a threaded bolt extending through the said perforations for clamping the base to the support, means for fixing the head of the bolt in a predetermined spaced relation to the support for permitting movement of the base longitudinally of the bolt, and a yielding means between the base and the support for yieldingly pressing the base into engagement with the head of the bolt and for retaining the base in spaced relation to the support.

4. A fastening member for securing a perforate base member to a support having a perforation aligned with a perforation in the base, comprising a threaded bolt extending through the said perforation for clamping the base to the support, a sleeve surrounding the bolt for positioning the head of the bolt in a predetermined fixed spaced relation to the support permitting movement of the base longitudinally of the bolt and a spring washer on the bolt between the base and the support for yieldingly pressing the base into engagement with the head of the bolt and for retaining the base in spaced relation to the support.

5. The combination with a perforate support and a base member having a plurality of perforations aligned with those in the support, of bolts extending through the aligned perforations and having base-engaging portions that will not pass through the perforations, means for spacing the said portions a predetermined distance from the support, and yielding means between the base and support for yieldingly retaining the base in engagement with the said portions.

In testimony whereof, I have hereunto subscribed my name this first day of July, 1922.

WILLARD H. KEMPTON.
